UNITED STATES PATENT OFFICE.

WILLIAM DIETER, OF BROOKLYN, NEW YORK, ASSIGNOR TO E. W. BLISS COMPANY, OF BROOKLYN, NEW YORK, A CORPORATION OF WEST VIRGINIA.

TORPEDO STEERING-GEAR.

1,233,761.

Specification of Letters Patent.

Patented July 17, 1917.

Application filed February 3, 1917. Serial No. 146,501.

To all whom it may concern:

Be it known that I, WILLIAM DIETER, a citizen of the United States of America, residing in the borough of Brooklyn, county 5 of Kings, in the city and State of New York, have invented certain new and useful Improvements in Torpedo Steering-Gears, of which the following is a specification.

This invention relates to means for steering 10 of automobile torpedoes under control of a gyroscope, or the latter might be substituted by any other equivalent directive means.

Torpedoes are steered on a sinuous course 15 which at frequent intervals crosses the theoretical course or line of aim. The present invention has for its object to bring the sinuous course into closer coincidence with the straight line which the torpedo should 20 follow, and thereby to increase the precision of the steering of the torpedo. In actual practice the present invention reduces the angle of deviation from the true course or line of aim to about one-fourth of that here- 25 tofore resulting; or in other words, it makes the direction of the torpedo four times as accurate. The invention is of special im- 30 portance when an "angle fire" is used, wherein the torpedo is launched with its rudder set to one side to steer a circular course until, according to the angular setting of the gyroscope, the mechanism is released and the normal steering on a straight line course is begun.

These results are accomplished by an improved construction of the pallet device used 35 for communicating the control from the gyroscope to the steering mechanism proper. The construction of the pallet is such that certain lost motion hitherto inherent in the 40 construction is eliminated, while at the same time any liability of jamming or injury is avoided.

The improved construction is shown in 45 the accompanying drawings, wherein,—

Figure 1 is a vertical longitudinal section of such parts of the gyroscope steering mechanism of the Bliss-Leavitt torpedo as are necessary to enable the present invention to be understood;

Fig. 2 is a plan of a portion of this mechanism;

Fig. 3 is a plan in horizontal section on the line 3—3, Fig. 5;

Figs. 4 and 5 are respectively front and 55 rear elevations of the pallet device;

Figs. 6 and 7 are horizontal sections there- 60 of on the line 6—6 in Fig. 1, showing the pallet in two different positions;

Fig. 8 shows the several parts separated, 65 each being in elevation, and two of the parts being partly in section;

Figs. 9 to 16 inclusive are diagrams of the 65 pallet, the purpose of which will develop as the description proceeds.

The control of steering mechanism from a gyroscope through a tappet device is set forth in principle in patent to Leavitt, No. 795,045, dated July 18, 1905. The mecha- 70 nism as subsequently applied to the Bliss Leavitt torpedoes is shown in the following 75 patents, namely,—

Leavitt, No. 925,710, June 22, 1909;

" " 1,080,116, Dec. 2, 1913;

Dieter, " 1,153,678, Sept. 14, 1915, 75 and the latter patent explains the operation under curved or "angle fire."

In such mechanisms the gyroscope carries a disk formed with a directive cam, toward and from which is rapidly reciprocated a 80 light pallet or two-armed piece (called in Patent No. 795,045 a "feeler") which gently touches the cam surface and receives there- 85 from a direction according to the angular position of the torpedo relatively to the gyroscope, and on its return movement acts as a tappet by striking a part or parts which in turn communicate movement to the valve of the steering engine or to other controlling 90 means for determining the movement of the rudder.

In the following description it will be assumed that the construction, otherwise than here shown, is the same as that in Patent No. 1,153,678 above referred to.

Referring to Fig. 1, the gyroscope A com- 95 prises the usual fly-wheel *a*, inner gimbal ring *b* and outer gimbal ring *b'*, the latter pivoted on a vertical axis and carrying a cam disk *B* against which works the pallet 100 *C* which is hung on the lower end of a vertical spindle *d* which has bearings in a sleeve *e* forming part of a slide *f* which is recipro- 105 cated by an eccentric *g*, so that the pallet *C* is caused to rapidly approach and recede from the cam disk. The upper end of the spindle *d* carries a tappet arm *h* which during the retreating movement may strike

either of two tappet levers i i' , whereby to displace these in either direction and thereby through connecting rods j k to shift the valve of the steering engine K , which in turn operates the rudder. This mechanism, being well understood, requires no further description.

To comprehend my invention it is necessary that the precise mode of operation of the old means be understood. This can best be understood by reference to the diagrams, Figs. 9 to 14. In Fig. 9 the cam disk B is shown with its cam projection m on the center, or in line with the direction of movement (line $\alpha-\alpha$) of reciprocation of the pallet C . In Fig. 9 the pallet is shown at the end of its backward or receding movement, and as in its mid-position. If in this position of the parts the pallet approaches the cam, its projecting fingers or pawls n n enter on opposite sides of the cam m , so that the pallet is not tilted, but may take the position shown in dotted lines. If, however, the cam is tilted a slight angle or partially off the line $\alpha-\alpha$, as shown in Fig. 10, the effect of the advancing movement of the pallet will be that one of its pawls would strike the cam and the other would clear it, thereby tilting the pallet to the position shown in Fig. 10. Such tilting to either side is the normal action, the intermediate position shown in Fig. 9 not occurring in ordinary practice. Being thus tilted, the return or retreating movement of the pallet causes its tappet arm h , which is likewise tilted into the path of one of the tappet levers i i' , to strike that lever and thereby shift the valve of the engine to throw the rudder. So long as the angular deflection of the cam is to one side, the tilting of the pallet is to that side (see Fig. 10). To provide for a considerable degree of angular deflection beyond that corresponding to the width of face of the cam m , it is customary to construct the cam disk with upper and lower ribs p p' , (Fig. 1) and to locate the respective pawls of the pallet at different levels, (Fig. 5) so as to engage these respective ribs so that the cam disk can be turned through perhaps 120 degrees from the normal position in case of an angle fire. The reciprocating and tilting action thus far described is the normal steering action.

55 Another operation occurs in practice, either on the testing stand or in an actual run in making an angle fire. In this operation the cam disk B swings or revolves (relatively to the torpedo and hence to the direction $\alpha-\alpha$); and in this movement the cam m enters into engagement with the pallet C , if the latter is advanced. On the testing stand the pallet may be standing stationary in its advanced position, in which case the cam m must be able to swing

through and rock the pallet and disengage itself therefrom, it being understood that any failure to do so would cause binding and distortion of the parts and would wreck the mechanism. This operation may be best studied on the assumption that the pallet is advanced and the cam is moving from below to above the pallet in the direction shown in Fig. 11. As the cam enters into engagement with the pallet the parts are in 75 the position shown in Fig. 10; when passing the center they occupy the position shown in Fig. 12, and on clearing the pallet the parts take the position shown in Fig. 13. It will be observed that the spindle d on 80 which the pallet is pivoted, instead of being in line between the ends of the pawls n n , is displaced backwardly a considerable distance therefrom. It is to this arrangement that the ability of the pallet to clear the 85 cam during the described swinging movement is due. This will be clear from the dotted lines in Fig. 12, which are reproduced in the diagram, Fig. 14, where c is the center of the spindle, r v is the arc of 90 movement of the tip of the pawl, c r is the radius of the pawl, c v is the final position of the radius after completing the movement, and r s is a line developed from r parallel with the direction of movement 95 $\alpha-\alpha$. There is thus a lost motion in lateral direction which is necessary to enable the cam to actuate and safely clear the pallet when the cam disk is turned while the pallet is advanced; and this lost motion is 100 the principal cause of lateral inaccuracy in steering in a mechanism having tappet action for communicating control from the gyroscope. It results that in normal steering the reciprocating pallet requires for 105 tilting it, a lateral movement of the cam which is as much greater than the theoretical as the distance of v from the line $\alpha-\alpha$ is greater than the distance of r from that line. The precise effect is modified also 110 partly by the minimum safe clearance to be allowed for the direct entry of the cam m between the pawls n n (see dotted lines in Fig. 9), and for the lateral swing of the tappet arm h before it will strike either 115 tappet lever i i' . For a given mechanical clearance necessary for safety, the extra clearance due to the rearward location of the center c involves that much greater margin of inaccuracy in the steering of the 120 torpedo.

With the old construction thus far described the result of these clearances in an actual torpedo is that the torpedo axis diverts laterally about one-half degree (30') between 12 rudder operations, so that when the torpedo axis is swinging off from the theoretical course or line of aim, it diverts about 15' from that course before the rudder is operated to steer it back onto and across such 125

course. In a straight fire with a short course this deviation is not serious; but with a long course or a curved fire it may become an important source of error. For example, with a 10,000 yard course a deviation of 15' would amount to about 44 yards at the target. Although this deviation on a straight fire is constantly corrected by an equal and opposite deviation, yet every torpedo has some tendency to drift laterally, and the less frequently this drift is corrected the more it affects the accuracy of the steering of the torpedo. On a curved or "angle fire" the torpedo steers a circular course for a predetermined number of degrees and then the steering is taken up by the gyroscope mechanism, which should cause the torpedo to steer on a tangent from said circle; but the precise direction of this tangent will be determined by the fractional part of the angular deviation between steering functions at which the angle fire control ceases and the gyroscopic steering mechanism begins to act, so that with a total deviation of one-half degree it becomes a matter of chance whether this entire deviation or any part thereof, or none, shall be impressed upon the ultimate course. Since a deviation of one-half degree on a 10,000 yard course amounts to 87.5 yards, the torpedo cannot, under the most favorable conditions, be accurate within this margin of error.

The facts thus stated show the importance, in order to obtain accuracy upon long ranges or with "angle fire," of being able to diminish the margin of lateral deflection between steering operations. This is accomplished by the new construction which will now be described.

Referring to Fig. 15, which is a diagram corresponding to Fig. 12, it is seen that the center or axis *c* of the spindle *d* has been displaced to *c'* at the intersection of the lines *x-x* and *y-y*, the latter line coinciding with the tips of the pallet pawls. This construction eliminates the lost motion already described and permits the pallet and cam to interengage with only sufficient mechanical clearance to avoid jamming during the normal reciprocating approach. When the cam is slightly deflected the pallet is rocked by it, as shown in Fig. 16, this rocking taking place around the new center *c'*. This new arrangement is found in practice to eliminate a very large proportion of the inaccuracy due to the causes already described.

This construction would be wholly impracticable in a torpedo because the cam, in the effort to swing through the approached pallet in the movement described with reference to Fig. 11, would almost inevitably jam and break the pallet mechanism. This is best understood from Fig. 16, where the cam *m* may be assumed to be moving down-

wardly, in which case it would strike squarely against the pawl *n* in front of it, and as neither part would yield, the pallet or its mounting would be broken. In the position shown in Fig. 15 a movement in either direction would be resisted by the perpendicular thrust and would be blocked. Hence, such a construction would inevitably result in disaster.

To avoid this the present invention provides the pallet with two pivotal centers, the main one, that for the spindle *d*, being at the point *c'*, while an auxiliary pivot is provided with its center at the point *c*, Fig. 12, or at or substantially the position of the center in the old structure. The former center *c'* is the one on which the pallet turns in the normal steering operations. The latter center is the one on which the pallet turns whenever necessary to free itself from the cam, and especially to enable the latter to swing through while on the testing stand or in the execution of a curved fire.

The construction will be best understood from Figs. 1 to 8 inclusive. Instead of the pallet *C* being fixed on the lower end of the spindle *d*, it is pivoted to a cross-head *q* which is fixed to the lower end of the spindle. The crosshead has four arms, one of which, *11*, forms the boss for inserting the screw *t* on which the pallet is pivoted to the crosshead; two lateral arms *12*, *12* are provided, having holes *13* in which rest loose pins *u u*. The fourth side of the crosshead has a boss receiving a screw *14*, on which is carried a spring *15* which presses against the middle of a cross-bar or equalizing lever *16*, the ends of which engage the rear ends of the pins *u* while their front ends passing through the arms *12* bear against upright pins *w w* fastened to the pallet *C*. The pins *u* are made, as shown in Fig. 8, with the thickened portion forming double shoulders, one of which receives the pressure of the spring through the cross-bar *16*, and the other abuts against the arm *12* of the crosshead *q* so that, as clearly shown in Fig. 6, the parts are held in their normal symmetrical position. If now a tilting thrust should come upon the pallet (as in the swinging through movement of the cam), the tilting effort would cause one of its pins *w* to press back one of the pins *u* (the other pin *u* remaining immovable), whereby the equalizing plate *16* acts as a lever, turning on the unmoved pin as a fulcrum, and transmitting the spring pressure to resist the displacement of the moved pin, as clearly shown in Fig. 7. Thus, in the swinging through movement of the cam the pallet has the same capacity for tilting and the same ability to clear itself as in the former construction, the only resistance encountered in such case being that of the spring *15*.

While the construction thus described is

believed the best for accomplishing this yielding mounting of the pallet, yet obviously various other constructions for similar purposes are known in the arts and any 5 suitable construction may be substituted as an equivalent.

It is found in actual practice that the improved construction thus described reduces the angle of divergence between the torpedo 10 axis and the steering axis necessary to reverse the rudder from 15' to less than 4'; that is, from one-quarter degree to one-sixteenth degree; in other words, it causes the rudder to shift four times as often, and with 15 one-fourth the angular divergence, and hence makes the torpedo four times as accurate in its steering. It results that the sinuous course of the torpedo swings only one-fourth as far as heretofore from the true 20 course, and hence the steering is corrected four times as often, so that the sinuous course approaches far more closely to the ideal straight course. Hence, theoretically, the extreme margin of error on a 10,000 25 yard course is reduced from 87.5 yards to less than 22 yards, an increase in accuracy which is particularly desirable in an angle fire.

It is essential to the reciprocal clearance 30 of the cam and pallet that one of these parts be capable of yielding movement and be provided with a spring to hold it in its normal position, this spring being strong enough to so hold it during normal operation, but capable of yielding to enable the parts to clear 35 in case the cam swings through the pallet while the latter is advanced. Conceivably, the cam might be the yielding member, but this would involve such practical difficulties 40 that I have found it far preferable to introduce the yielding function in the mounting of the pallet. My invention is not limited to the introduction of the yielding means between the pallet and the reciprocating 45 spindle d , it being within my invention to provide any yielding means whereby the pallet may disengage itself from the cam during the lateral movement of the latter.

I claim as my invention:

50 1. In a torpedo steering mechanism comprising a controlling cam and a reciprocating pallet pivotally mounted on an upright spindle, such spindle having its axis located approximately in line between the pallet pawls, and yielding means whereby the cam and pallet may reciprocally disengage during a rotative movement of the cam.

2. In a torpedo steering mechanism com-

prising a controlling cam and a reciprocating 60 pallet pivotally mounted on an upright spindle, such spindle having its axis located approximately in line between the pallet pawls, and the pallet having an independently yielding mounting adapted to enable it to free itself from the cam when the latter is moving rotatively while the pallet is advanced.

3. In a torpedo steering mechanism comprising a controlling cam and a reciprocating 70 pallet pivotally mounted on an upright spindle, such spindle having its axis located approximately in line between the pallet pawls, and the pallet pivoted relatively to said spindle upon a pivotal center displaced 75 from the spindle axis to enable the pallet to yield independently to clear itself from the cam.

4. In a torpedo steering mechanism comprising a controlling cam and a reciprocating 80 pallet pivotally mounted on an upright spindle, such spindle having its axis located approximately in line between the pallet pawls, a head carried by said spindle, the pallet pivoted to said head upon a center displaced rearwardly from the spindle axis, 85 and yielding means for holding the pallet in normal relation to the head.

5. In a torpedo steering mechanism comprising a controlling cam and a reciprocating 90 pallet pivotally mounted on an upright spindle, such spindle having its axis located approximately in line between the pallet pawls, a head carried by said spindle, the pallet pivoted to said head upon a center 95 displaced rearwardly from the spindle axis, shouldered pins carried by the head, and a spring acting through said pins on the pallet to hold it normally in fixed relation to the spindle and head.

6. In a torpedo steering mechanism comprising a controlling cam and a reciprocating 100 pallet pivotally mounted on an upright spindle, such spindle having its axis located approximately in line between the pallet pawls, a head carried by said spindle, the pallet pivoted to said head upon a center 105 displaced rearwardly from the spindle axis, shouldered pins carried by the head, a lever plate engaging said pins, and a spring pressing against said plate and acting through the plate and pins to hold the pallet normally in fixed relation to the spindle and head.

In witness whereof, I have hereunto 115 signed my name.

WILLIAM DIETER.
